UNITED STATES PATENT OFFICE.

JOHN PARENT, OF BRUNSWICK, MAINE.

THILL-CO尤LING JACK.

SPECIFICATION forming part of Letters Patent No. 279,005, dated June 5, 1883.

Application filed April 7, 1883. (No model.)

To all whom it may concern:

Be it known that I, JOHN PARENT, a citizen of the United States, residing at Brunswick, in the county of Cumberland and State of Maine, have invented certain new and useful Improvements in Devices for Setting Thill-Rubbers, of which the following is a specification, reference being had therein to the accompanying drawings.

10 My invention relates to devices for inserting thill-rubbers; and it consists in an arrangement of levers, one of which clasps the thill, while another, to which power is applied, rests against the axle, compressing the rubber and

15 allowing the bolts to be taken out or put in. In my drawings, Figure 1 shows a side view of my device attached to the thill and in position to compress the rubber. Fig. 2 shows a back view of the same. Fig. 3 shows a plan or

20 top view. A is an elbow-lever, the upper end of which is formed into a clasp or hook which embraces the thill. The spur *a* projects underneath the thill in such a manner that when the upper end of lever A is hooked on the thill the point of the spur *a* will bear against the under side of the thill and form a stop. The two straight levers B B are pivoted to the lower end of the lever A by means of the axle

25 A'. The levers B B are provided with holes *b b*. The bifurcated lever C is hung to the levers B B by means of the pin D, which passes through the holes *b b*. The pin D has a thumb-piece on one end, by which it may be

handled. The upper end of the lever C is 35 formed into a handle.

When a rubber, E, is to be inserted it is placed in position behind the thill, and before being compressed it is always wide enough to cover the holes through which the bolt H 40 passes. The lever A is now hooked over the thill, as shown, and the lever C adjusted on the levers B B, so that a purchase may be obtained against the axle. If now the thill is held by the hand and force applied on the 45 end of lever C, as shown by the arrow, the thill is pressed back against the rubber, which is compressed, thus allowing the bolt H to be put in. By the same process the bolt H may be withdrawn. The levers A and C, where 50 they come against the carriage, may be covered with leather to prevent the varnish from being scarred. The two levers B B may be replaced by one lever hung to levers A and C in a manner substantially as here shown; 55 but I consider the present form better.

I claim as my invention—

The device for inserting thill-rubbers, consisting of the lever A, one end of which hooks over the thill, combined with the levers B B, 60 and the lever C, having a handle on its upper end, substantially as shown and described.

In testimony whereof I affix my signature in presence of two witnesses.

JOHN PARENT.
